ARTIFICIAL LIMB AND METHOD OF
MAKING THE SAME

Theodore John Schmidt, Portland, Oreg.

Application February 11, 1946, Serial No. 646,832

5 Claims. (Cl. 3-2)

The present invention relates to artificial limbs and provides a novel structure and method of making the same.

The principal objects of the invention are to provide an artificial body member, in the form of a leg, thigh, upper arm or forearm, which will be simple and inexpensive to make, light in weight, rigid and durable in use, and well adapted to receive end connections for jointing to the member a cooperating element such as another limb member or an artificial hand, foot or the like of any more or less conventional construction.

An important object of the invention is to provide a method by which artificial limbs of any predetermined length and contour can be assembled from standard stock parts associated in any predetermined number and arrangement.

Further objects include the provision of an artificial limb which can be made from standard wood stock, such as plywood sheets, by workmen having no special qualifications or skill beyond ordinary woodworking ability, employing nothing more than standard woodworking equipment.

Other and further objects of the invention will be made apparent to those skilled in the art by reference to the accompanying drawing and following description thereof which disclose certain preferred embodiments of the invention.

In the accompanying drawing:

Figure 1 is a side elevational view of a stack of individual component elements of an artificial leg assembled in accordance with one of the preliminary steps of the method;

Fig. 2 is a similar view of the assembly after trimming to the desired contour of an artificial leg, and showing also a conventional form of artificial foot jointed to the assembly;

Fig. 3 is a longitudinal median sectional view of the finished artificial leg;

Fig. 4 is an exploded view in perspective of three of the component elements of a limb made according to the principles of the invention; and

Fig. 5 is a side elevational view of an upper arm and forearm embodying the principles of the invention, jointed together and having an artificial hand of conventional form connected thereto.

The invention comprises essentially the assembly of a plurality of individual discs or annuli to provide a built-up stack having the shape of the desired leg or arm member. The individual elements are adhesively bonded together and are preshaped and selected relatively to each other to provide any desired external contour and overall length. The preferred material of which

the individual disc or annulus elements are made is plywood, i. e., sheets of wood veneer adhesively bonded together with their grains crossing each other. Such plywood is a standard article of commerce which is well known and requires no further description or identification.

From such sheets of plywood a plurality of annuli 1 are cut in a number of different sizes having external peripheries varying from that of the thinnest ankle or wrist which it may be desired to reproduce in an artificial leg or arm to the thickest calf or biceps that it may be desired to simulate. As shown in Fig. 4, each of these annuli 1 has an axial thickness equal to that of the plywood sheet from which it is cut and each has a radial width A sufficient to give the element appropriate strength, i. e., a width of as little as one-quarter or three-eights inch to as much as one inch. These dimensions are not critical and can be varied at will without departing from the principles of the invention.

The annuli are made in graduated sizes, in respect to external diameter, in steps of about one-quarter inch, and a large number of specimens of each of the different sizes are made.

A smaller number of strengthening discs 2 are also made in the same sizes as the annuli 1. The discs 2 differ from the annuli 1 by being substantially solid but they may have central and marginal openings 3 drilled or otherwise formed through them to reduce their weight. Despite these weight-reducing openings the discs are substantially more rigid than the annuli because of the strengthening or reinforcing substantially radial ribs 4 defined by the openings.

With a sufficient number of the discs and annuli fabricated and classified according to size, a selection of appropriate sizes is made in accordance with some predetermined shape and length of limb to be manufactured. Assuming such limb is the leg shown in Figs. 2 and 3, annuli and discs will be selected and stacked in the manner indicated in Fig. 1. Each element of the stack is coated on its flat, side surfaces with some appropriate waterproof adhesive, such as an artificial resin cement, and the stack is then mounted in a glue press until the adhesive has set. The result is the rough approximation of an artificial leg shape as shown in Fig. 1.

It will be noted that the surface of the body shown in Fig. 1 is stepped and discontinuous, a condition which results from the graduated sizes and the cylindrical shape of the outer walls of the several annuli and discs. This outer surface is dressed in any convenient manner, as by

turning the body in a lathe, followed by a sanding operation. This results in the formation of the smooth, continuous outer surface shown in Figs. 2 and 3. The result is an artificial leg which closely simulates the shape of a natural leg. The upper and lower ends of the body may be closed by solid discs, indicated at 5 in the figures, and these end discs may be drilled or otherwise treated to provide sockets, pivots or other types of connection for an artificial foot 6 at the bottom or straps and the like, not shown, at the top for connection to a stump.

The completed member may have its surface finished by any paint, varnish or the like which is suitable for use on wood.

Fig. 5 indicates how an appropriate selection of discs and annuli elements can be assembled to provide an upper arm 7 and a forearm 8 and how the latter may have an artificial hand 9 secured to it and how it may be connected to the upper arm by a pivot joint 10.

The frequency at which the strengthening discs 2 are interposed in the stack will be determined by the radial width of the annuli 4, the length of the member to be made, the desired rigidity and strength of the member, and other factors. In a leg of approximately eighteen inches length, about three such strengthening discs will generally be found sufficient, as shown in Fig. 3. Under some circumstances fewer discs or no discs at all may be used.

The finished member is extremely light and very durable. It is quite rigid, yet it has sufficient flexibility to yield slightly without breaking under the impact of unusual blows and strains. Because the elements are made of plywood, with their alternatively crossed grains, the assembly does not warp or split in the way that solid wooden artificial body members are apt to do.

The invention is capable of being embodied in other and differently modified forms, all within the scope of the appended claims.

I claim:

1. A method of making an artificial limb comprising forming from sheets of plywood, each comprising a plurality of layers of wood adhesively bonded together with the grains of adjacent layers crossing each other at an angle, a plurality of annuli having flat side surfaces and

outer peripheries of different size, adhesively securing said surfaces of selected annuli to each other to provide a stack having the approximate over-all shape of a natural limb but differing externally therefrom by having an outer surface characterized by angular offsets at the junctions of adjacent annuli, and then trimming the outer surface of the stack to remove said offsets and cause the peripheries of the annuli to merge into each other and thereby simulate more nearly the shape of a natural limb.

2. An artificial limb comprising a multiplicity of annuli of plywood, each annulus having a plurality of thin layers of wood adhesively bonded together with the grains of adjacent layers crossing each other at an angle and all of said annuli being adhesively bonded coaxially together to form an elongated stack having a generally hollow interior and having a relatively smooth continuous outer surface simulating the contour of a natural limb.

3. The combination claimed in claim 2 including a relatively solid disc of said plywood interposed between certain of said annuli for imparting increased rigidity to the stack.

4. The combination claimed in claim 2 including a plurality of relatively solid discs of said plywood interposed at spaced intervals between certain of said annuli for imparting increased rigidity to the stack.

5. The combination claimed in claim 2 including a relatively solid disc of said plywood interposed between certain of said annuli for imparting increased rigidity to the stack and said disc having a hole formed therein for decreasing its weight.

THEODORE JOHN SCHMIDT.
